UNITED STATES PATENT OFFICE

PIERRE J. CHÉRON, OF STRATFORD, CONNECTICUT, ASSIGNOR TO THE MOTOMETER COMPANY, INC., OF LONG ISLAND CITY, NEW YORK, A CORPORATION OF NEW YORK

DESIGN FOR AN AUDIBLE TRAFFIC-WARNING DEVICE FOR VEHICLES

Application filed July 15, 1929. Serial No. 32,054. Term of patent 14 years.

To all whom it may concern:

Be it known that I, PIERRE J. CHÉRON, a citizen of the United States, residing in Stratford, county of Fairfield, and State of Connecticut, have invented a new, original, and ornamental Design for Audible Traffic-Warning Devices for Vehicles, of which the following is a specification, reference being had to the accompanying drawing, forming a part thereof.

Figure 1 is a front elevation of an audible traffic warning device for vehicles embodying the design of the present invention; and

Figure 2 is a plan view of the same.

I claim:

The ornamental design for an audible traffic warning device for vehicles substantially as shown.

PIERRE J. CHÉRON.
